[57] CLAIM

The ornamental design for a personal telecommunications terminal, as shown and described.

DESCRIPTION

FIG. 1 is a perspective view of the personal telecommunications terminal showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a top fragmentary view of the panel which has been enlarged for clarity of illustration; and,

FIG. 8 is a bottom view thereof.

The broken line showings of FIGS. 1-8 are for illustrative purposes only and form no part of the claimed design.
